UNITED STATES PATENT OFFICE.

JOHN B. WEST, OF SYRACUSE, NEW YORK.

AUTOMATIC REGULATOR FOR INTERNAL-COMBUSTION ENGINES.

1,317,844.

Specification of Letters Patent.

Patented Oct. 7, 1919.

Application filed September 26, 1917. Serial No. 193,383.

To all whom it may concern:

Be it known that I, JOHN B. WEST, a citizen of the United States, and a resident of Syracuse, in the county of Onondaga and State of New York, have invented a new and useful Automatic Regulator for Internal-Combustion Engines, of which the following is a specification.

This invention has for its object an automatic regulator for a power plant including an internal combustion engine, and an electric generator, which regulator automatically regulates the flow of air or other gas into the intake manifold of the engine and 10 is controlled by the current generated by the generator of the electrical system of the power plant. It further has for its object a regulator which is simple and compact in construction, economical to manufacture, 15 readily applicable to the power plant, and highly efficient and durable in use; and the invention consists in the combinations and constructions hereinafter set forth and claimed.

25 In describing this invention, reference is had to the accompanying drawings in which like characters designate corresponding parts in all the views.

Figure 1 is a front elevation of one form 30 of my regulating means.

Fig. 2 is an elevation thereof, the cover and parts thereof being removed.

Fig. 3 is a sectional view on line 3—3, Fig. 2.

35 Fig. 4 is an elevation of an internal combustion engine, and the contiguous portion of a motor vehicle showing my instrument applied thereto.

Fig. 5 is a diagrammatic view showing 40 my controlling device connected in the electrical system of a motor vehicle.

My regulator for power plants is automatically operated by the fluctuations in the generator circuit so that if the engine runs 45 at such speed as to cause the generator to generate a current of say eight (8) amperes, my device opens the air conduit so that air is taken into the manifold and if speed of the engine drops so that it runs at such 50 speed as to cause the generator to generate a current of two (2) amperes, the air valve is closed so that a richer mixture is taken into the engine cylinders.

Assuming that the device is set to require 55 a current of eight (8) amperes to open the air valve, a current of less number of am-

peres will be required to hold the valve open as for instance, two (2) amperes, and therefore the valve does not open until the generator is generating a current of eight (8) amperes and does not close until the current generated drops to two (2) amperes. The figures 8 amperes and 2 amperes are arbitrarily chosen for the purpose of illustration. The regulator is usually set to open 60 the air valve after the generator has developed generating speed so that when the engine has developed a speed greater than generating speed it can thereafter be run with less hydrocarbon or other fuel as the valve remains open during the time the generator is generating a current up to maximum or above eight (8) amperes or other predetermined number of amperes. When the speed of the engine and hence the speed 70 of the generator drops a certain amount, the air valve closes. The operation of the valve is controlled by the engine through the electric generator and not mechanically by the engine.

This invention comprises a conduit through which air or other gas is supplied to the intake manifold, usually between the carburetor and the engine cylinders or to the carburetor above the throttle valve, a 80 valve for controlling the flow through said conduit, and means controlled by the current in the generator circuit for opening and closing the valve. Said means preferably includes an electromagnetic element connected in the generator circuit, and operable by the rise and fall of the current in said circuit.

The regulator as here shown is a unitary structure readily connectible to the engine 95 and in the generator circuit, and comprises a casing including a base 1, and cover 2, the base being formed with a passage having an inlet and means for connection to a pipe leading to the engine manifold, a valve 3 100 for controlling the flow through said passage, an electromagnet 4 including a movable element arranged within the influence of the field of the magnet as a core lever 5, and means connecting the core lever 5 to the 105 valve 3.

The base 1 is in the form of a disk forming the body thereof, and a radially extending stem portion 7, the stem including a portion 8 extending radially on the back of the body or disk and usually to the center thereof, and terminating in an axially ex-

tending nipple 9 for connection to a pipe 10 leading to the intake manifold 11 of the internal combustion engine 12, the pipe 10 being usually connected between the carburetor 13 and the cylinders of the engine.

The cap or cover 2 is mounted on the base 1 and includes an annular wall forming the sides of the casing, this wall being formed with a cut-out at 14 for fitting over the upper end of the stem 7 at the front of the body or disk. The stem 7 is formed with two passages 15, 16 connected by a transverse passage 17 one of which as 15 opens through the upper end of the stem in front of the body or disk and into the interior of the space inclosed by the cover 2, and the other 16 of which extends parallel to the former passage in the part 8 of the stem and communicates with the axial passage 18 in the nipple 9. The passage 15 communicates with the outer air through an inlet 19.

The core lever 5 has an arc-shaped portion 20 movable through the coils of the electromagnet element 4, and a radially extending portion 21 pivoted at 22 to the body or disk of the base 1 at the center of the arc-shaped portion and slightly below the center of the disk 1. It is also provided with a weighted arm 23 extending on the opposite side of the axis 22 from that on which the arm 21 is located, this weighted arm 23 balancing or partly balancing the portions 20, 21 so that the lever and valve 3 are not affected by vibrations of the engine.

This core lever 5 is usually sheet metal and in order that the weighted arm 23 may be heavy enough to perform its function within the available space, it is bent U-shaped as shown in Fig. 3 and its extreme end is also mounted on the pivot 22.

The means for transmitting the motion of the core lever 5 to the valve 3 comprises a lever as a V-shaped angle lever 24 pivoted at its angle at 25 to the base 1 and having one arm as 26 slidably connected to the core lever 5 and its other arm pivoted at 27 to a link 28 extending into the passage 15 and being pivoted to the valve 3.

The arm 26 slidably engages a pin 29 extending between the double portion of the weighted arm 23 below the pivot 22.

The valve 5 is a balanced valve; that is, it is balanced so as to be unaffected by the suction created in the passage 15, and as here shown it is formed with a double head connected by a stem 30, the opposing faces of the heads being obviously acted upon equally by the suction. Owing to the balanced valve 3 and balanced core lever 5 this instrument operates accurately under the trying conditions it is subjected to.

The valve is shown in its closed position in Fig. 3 in which the upper head of the valve 3 is cutting off the inlet 19.

When the valve is raised, the upper head moves above the inlet 19 so that air can enter through the passage 15.

Means is provided for adjusting the pull of the magnet on the core 5 in order to adjust the device to different engines and generators, and this adjustment is effected by changing the relative starting positions of the core and magnet coils. Preferably, the coils 4 are shiftable relatively to the core 5 and as here shown the coils are mounted upon a support carried by a carriage 31 which is pivoted on the axis 22 and movable about said axis. Opposite ends of the winding of the magnet are flexibly connected by wires to suitable binding screws or devices 33, 34.

The pivot 22 extends through a hole in the top of the cover 2 and has loosely mounted thereon a pointer 35 which is held in position by a nut 36. The pointer moves over a graduated scale 37 on the face of the cover 2 and indicates on the scale the adjustment or pull of the magnet 4 relatively to the amount of current generated. For instance, if the current carried by the generator circuit is eight (8) amperes, and the ammeter in said circuit shows eight (8) amperes, the pointer 35 can be adjusted so that the valve will open at eight (8) amperes. The pointer 35 is connected to the carriage 31 by means of a stem or rod 38 extending from the carriage 31 and through a slot 39 in the cover, the pointer being held in its adjusted position by a nut 40 screwing on the threaded end of the stem 38 against the cover.

The pipe 10 may be provided with a suitable valve for opening and closing the same more or less to adjust the device to engines of different sizes. For instance, in a larger engine the valve would be open farther than in a smaller engine and by reason of this valve 41 and the adjustability of the pull of the magnet, an instrument of a given size can be adapted to various sizes of engines and generators and conditions.

This instrument is connected up with the coils 4 in series with the generator circuit between the generator and the load as shown in Fig. 5 in which the engine 12 is shown as connected to the generator 42 by means of a belt 43 and the generator circuit includes a load comprising the usual lamps 44, storage battery 45, and an automatic cut-out switch 46 which opens the circuit when the generator is running below generating speed, to prevent the battery from discharging back into the generator as will be understood by those skilled in the art. When so connected, the instrument is not affected by variations in the load circuit when the lights are on or when the battery is working, and hence the instrument is only affected by fluctuations due to the raising and lowering of the speed of the generator.

5 In operation, when the instrument is applied to an engine, the point at which the indicator 35 should be set is readily found and set at the point at which the engine operates most effectively.

10 The valve 3 is normally closed and as the engine speeds up and reaches a predetermined speed, it causes the generator to generate current of predetermined amperage which energizes the magnet 4 to operate the core lever 5 and lift the valve 3 to open position.

15 When the speed drops a predetermined amount and less current is generated, the magnet becomes deenergized sufficiently to permit the valve to close, so that a richer mixture is taken into the manifold, that is, a mixture which is unmixed with air other than the air drawn in through the carbureter.

20 The point at which the indicator 35 should be set differs for each engine and by reason of this adjustment the device is applicable to all engines.

25 This device is particularly advantageous in that it can be relied upon to work automatically under all conditions and further in that it admits air into the intake manifold above the carbureter and the throttle so that when the valve opens, each cylinder at the end of the suction stroke of the piston therein, is filled as completely as possible with gas and air at normal pressure, it being understood that it is impossible to 30 fill a cylinder completely at normal, that is atmospheric pressure by the suction created by the piston. Hence, upon compression, when the engine is throttled the small charge of gas as distinguished from the gas plus

35 40 the air is compressed to the same extent as a cylinder full of gas (without additional air) when the throttle is wide open. Hence, the small charge will ignite almost as readily as a full or unthrottled charge or at least much more readily than a throttled charge without auxiliary air. As the speed of the engine increases under this operation, and as the larger air passage is through the carbureter, proportionately more air is drawn in through the carbureter to form a richer mixture and free air through the air valve, hence the compression increased and the power and speed accelerated. Hence, the throttle can be closed farther to maintain a 45 predetermined speed thus saving gasolene. This operation is due to the fact that the valve opens wide and is not affected or regulated by the suction or anything that causes it to fluctuate.

50 55 Owing to the fact that the valve is wide open, the suction or pull in the cylinder is relieved when the gas passing through the carbureter "wicks draws" or is not sufficient to fill the space of the cylinder at atmospheric pressure; and in addition as before

stated, the air filling the cylinder brings the compression up to normal so that a small charge fires more readily than the usual throttled charge without additional air.

55 In fact, by actual test in the practical use 70 on automobiles a saving of from 25% to 33% in fuel as well as gain in power is obtained, and by dynamometer test a saving in gasolene of 20% at all engine speeds is shown as well as increase in power. 75

What I claim is:

1. The combination with an internal combustion engine, and an electric generator connected to the engine to be actuated thereby, of an air conduit connected to the intake 80 above the throttle, a valve in the air pipe, and electro-magnetic means connected in circuit with the generator to open and hold open the valve when the engine attains a predetermined speed and the generator produces a current of predetermined value, substantially as and for the purpose described. 85

2. An automatic regulator for power plants including an internal combustion engine and an electric generator driven by 90 the engine, the regulator comprising a casting including a base, and a cover, the base having an air passage, and an inlet opening into said passage, a valve for controlling the flow of air through the passage, an electromagnet including two elements mounted on the base, one element having windings connected in the generator circuit, and the other element being arranged to be acted upon by the magnetic field of the windings, 95 one of said elements being movable, and power transmitting means between the movable element and the valve, substantially as and for the purpose specified. 100

3. An automatic regulator for power 105 plants including an internal combustion engine, and an electric generator driven by the engine, the regulator comprising a base formed with an air passage having an inlet, a valve for opening and closing the passage, 110 the valve being balanced against the suction of the engine, an electromagnet having windings connectible in the generator circuit and a movable core mounted in the base and connected to the valve, substantially as and for 115 the purpose described.

4. An automatic regulator for power 120 plants including an internal combustion engine, and an electric generator driven by the engine, the regulator comprising a base formed with an air passage having an inlet, a valve for opening and closing the passage, 125 an electromagnet having windings connectible in the generator circuit, a movable core mounted on the base, and power transmitting means between the core and the valve, substantially as and for the purpose set forth.

5. An automatic regulator for power 130 plants including an internal combustion en-

gine, and an electric generator driven by the engine, the regulator comprising a base formed with an air passage, and an inlet, a valve for controlling the flow of air through said inlet, an electromagnet coil mounted on the base, a balanced pivoted core arranged within the influence of the coils, and means for transmitting the motion of the core to the valve, substantially as for the purpose described.

6. An automatic regulator for power plants including an internal combustion engine, and an electric generator driven by the engine, the regulator comprising a base formed with an air passage, and an inlet, a valve for controlling the flow of air through said inlet, electromagnetic means mounted on the base including a pivoted core having an arc-shaped portion concentric with the pivot and movable through the coils of the magnet, and means for transmitting the motion of the core to the valve, said means including a lever, one arm of which is slidably connected to one of the parts it connects and pivotally connected to the other of said parts, substantially as and for the purpose specified.

7. An automatic regulator for power plants including an internal combustion engine, and an electric generator driven by the engine, the regulator comprising a base formed with an air passage, and an inlet, a valve for controlling the flow of air through said inlet, electromagnetic means mounted on the base including a pivoted core, power transmitting means between the core and the valve comprising a lever pivotally connected to the valve and slidably engaged with the core lever, substantially as and for the purpose set forth.

8. An automatic regulator for power plants including an internal combustion engine, and an electric generator driven by the engine, the regulator comprising a base formed with an air passage having an inlet, a balanced valve for controlling the flow into the passage through the inlet, and electromagnetic means for operating the valve including a balanced core lever, substantially as and for the purpose described.

9. An automatic regulator for power plants including an internal combustion engine, and an electric generator driven by the engine, the regulator comprising a base and a cap detachably mounted on the base, the base comprising a body provided with a radial stem portion extending on the back of the base, an air passage extending lengthwise of the stem and opening through the inner end thereof in front of the body of the base, a passage extending lengthwise of the stem parallel to the former passage in the rear of the body of the base and being connected to the former passage and having an outlet located at the rear of the body, a valve

in the former passage, an electromagnet mounted on the front of the body, a core lever pivoted to the base and extending through the magnet, and means including a part extending into the upper end of the former passage for transmitting the motion of the core lever to the valve, substantially as and for the purpose specified.

10. An automatic regulator for power plants including an internal combustion engine, an electric generator driven by the engine, the regulator comprising a casing including a base, and a cover, the base having an air passage, and an inlet opening into said passage, a valve for controlling the flow of air through the passage, an electromagnet including two elements mounted on the base, one element having windings connected in the generator circuit, and the other element being arranged to be acted upon by the magnetic field of the windings, one of said elements being movable, and power transmitting means between the movable element and the valve, one of said elements being shiftable relatively to the other to change the starting position thereof relatively to the other, substantially as and for the purpose set forth.

11. An automatic regulator for power plants including an internal combustion engine and electric generator driven by the engine, the regulator comprising a casing including a base, and a cover, the base having an air passage, and an inlet opening into said passage, a valve for controlling the flow of air through the passage, an electromagnet including two elements mounted on the base, one element having its winding connected in the generator circuit, and the other element being arranged to be acted upon by the magnetic field of the windings, one of said elements being movable, and power transmitting means between the movable element and the valve, one of said elements being shiftable relatively to the other to change the starting position thereof relatively to the other, and means for shifting said element, substantially as and for the purpose described.

12. An automatic regulator for power plants including an internal combustion engine, and an electric generator driven by the engine, the regulator comprising a base formed with an air passage, and an inlet, a valve for controlling the flow of air through said inlet, electromagnetic means mounted on the base including a pivoted core within the influence of the magnet, and means for transmitting the motion of the core to the valve, the coils of the magnet being shiftable relatively to the core, and means for shifting said coils and holding them in their adjusted position, substantially as and for the purpose specified.

13. An automatic regulator for power

plants including an internal combustion engine, and an electric generator driven by the engine, the regulator comprising a base formed with an air passage, a valve for opening and closing the passage, a carrier mounted on the base, a magnet mounted on the carrier, an armature element located within the influence of the magnet, power transmitting means between the armature

and the valve, and means for shifting the 10 carrier, substantially as and for the purpose set forth.

In testimony whereof I have hereunto signed my name, at Syracuse, in the county of Onondaga and State of New York, this 15 20th day of September, 1917.

JOHN B. WEST.
